UNITED STATES PATENT OFFICE

2,183,203

HIGH FREQUENCY AMPLIFIER

Waldemar J. Poch, Collingswood, N. J., assignor
to Radio Corporation of America, a corpora-
tion of Delaware

Application March 28, 1936, Serial No. 71,364

1 Claim. (Cl. 179—171)

My invention relates to high frequency amplifiers and particularly to television receiver amplifiers.

It is often desirable to vary the frequency response characteristic of an amplifier. In television receiver amplifiers, especially, it is desirable that they be adjustable for the purpose of varying the relative amplification of the high frequency components of an incoming picture signal. It may also be desirable in some instances to vary the relative phase of different frequency components of a signal.

In my Patent No. 2,122,990, which is assigned to the Radio Corporation of America, I describe and claim a television receiver having adjustable means for varying its frequency response characteristic. In that application I point out that if a television receiver is tuned away from one transmitter station to a second transmitter station which transmits more high frequency components of a picture signal than the first transmitter, the picture at the receiver will have a "bas-relief" appearance. To overcome this, the receiver must be adjusted to amplify the higher frequency components to a less degree.

On the other hand, if the receiver is tuned back to the first transmitter station, it is desirable to increase the high frequency response of the receiver so that the picture will contain a maximum of detail. There are various other reasons for making the high frequency response of a television receiver adjustable. For example, if there is considerable interference, a picture may be improved by lowering the high frequency response whereby "noise" in the picture is reduced. As interference or "noise" is generally at the higher frequencies, the loss of detail in a picture is often less objectionable than the "noise" included at these frequencies.

It is an object of my invention to provide an improved method of and means for varying the frequency response characteristic of an amplifier.

A further object of my invention is to provide an improved method of and means for controlling the degree of amplification of the high frequency components of a signal as compared with the amplification of its low frequency components.

A further object of my invention is to provide an improved method of and means for controlling the amplification and/or phase of the high frequency components of a signal as compared with the amplification and/or phase of its low frequency components.

A still further object of my invention is to provide an improved television receiver.

In a preferred embodiment of my invention the picture signal is supplied from an amplifier tube to the input circuits of two amplifier channels, one channel being designed to amplify all components of the picture signal a fixed amount, and the other channel being designed to amplify the high frequency components substantially to the exclusion of the low frequency components. The two amplifier channels have a common output circuit whereby their outputs add to give the desired resultant picture signal. The second channel includes adjustable means for determining the amount the high frequency components are amplified whereby the high frequency content of the resultant signal may be controlled.

Other objects, features, and advantages of my invention will appear from the following description taken in connection with the accompanying drawings in which

Figure 1 is a circuit diagram of a television receiver amplifier embodying my invention, and

Figs. 2 and 3 are circuit diagrams of other embodiments of my invention.

Referring to Fig. 1, my invention is shown applied to a television receiver which may include a heterodyne receiver portion indicated at 1. This portion of the receiver preferably includes an automatic volume control circuit for supplying a signal constant amplitude to the first video amplifier tube 2. The amplifier tube 2 may be of the screen grid type having a cathode 3, a control grid 4, a screen grid 6 and a plate 7. A grid biasing battery 8 or other suitable voltage source shunted by a potentiometer 9 is provided, the control grid 4 being connected through a grid resistor 11 and a variable tap 12 to a point on the potentiometer 9. The variable tap 12 may be moved along the potentiometer by rotating a knob, indicated at 13, on the front of the television receiver for the purpose of controlling the contrast of the picture. The picture signals are supplied through a coupling condenser 14 to the control grid 4.

A suitable positive potential is supplied through a filter resistor 16, a peaking coil 17 and a plate resistor 18 to the plate 7 of the amplifier tube 2. The filter resistor 16 is shunted by the usual filter condenser 19.

The picture signal appearing in the output circuit of the amplifier tube 2 is supplied to two amplifier channels 21 and 22. The first channel 21 includes an amplifier tube 23 which may be of

the three-element type having a cathode 24, a control grid 26 and a plate 27. The control grid 26 is maintained at a suitable negative bias by suitable biasing means such as a biasing battery 5 28, the grid 26 being connected through a grid resistor 29 and the biasing battery 28 to the cathode 24. Picture signal is supplied to the control grid 26 through a coupling condenser 31 which is connected between the plate 1 of the amplifier 10 tube 2 and the control grid 26. It will be noted that the input circuit of the amplifier tube 23 is thus connected across both the plate resistor 18 and the peaking coil 17 whereby all picture signal 15 components are supplied thereto with substantially equal amplitude.

A suitable positive potential is supplied to the plate 27 of the amplifier tube 23 through a filter resistor 32, a peaking coil 33, a plate resistor 34 and a second resistor 36. The filter resistor 32 20 is by-passed by the usual filter condenser 37.

The resistor 36 is provided between the plate 27 and the plate resistor 34 for two reasons. In the first place, it lowers the gain of the tube 23 a certain amount so that more effective control is provided by the tube 42. In the second, and more important, place it reduces the high frequency response of the channel 21 whereby it is possible by actuation of the control knob 53 to vary the combined high frequency response of the two 25 channels 21 and 22 from a value which is too low to one which is too high. The resistor 36 causes loss of highs for the reason that the tube electrode capacities are between ground the junction point of resistors 34 and 36. It may be mentioned, 30 by way of example, that the resistor 36 may have a value of 10,000 ohms and the resistor 34 a value of 6,000 ohms.

The picture signal appearing across the plate resistor 34 and peaking coil 33 is supplied to an 40 output tube 38 which, in turn, supplies the picture signal to the control grid 39 of the cathode ray receiver tube 41. The grid condenser 40 and grid resistor 45 are given suitable values to provide automatic background control as described and 45 claimed in my application Serial No. 718,192, filed March 30, 1934, and assigned to the Radio Corporation of America.

The second channel 22 includes an amplifier tube 42 which may be of the screen grid type, 50 having a cathode 43, a control grid 44, a screen grid 46, and a plate 47. Suitable variable bias means is provided, this being a biasing battery 48 which is shunted by a potentiometer 49 in the particular circuit illustrated. The control grid 44 55 is connected through a grid resistor 51 and a variable tap 52 to a point on the potentiometer 49. As in the case of the first described amplifier tube 2, the variable tap 52 may be moved along the potentiometer 49 by rotating a knob indicated at 60 53 which is located on the receiver panel.

In one embodiment of my invention the input circuit of the amplifier tube 42 is not connected across the entire output circuit of the amplifier tube 2, but, instead, is connected across the peaking coil 17 only. This connection is from the control grid 44 through a coupling condenser 54, a switch arm 56 and a switch contact point 57 to the junction point of the peaking coil 17 and the plate resistor 18. It will be evident that the signal 65 appearing across the peaking coil 17 has the high frequency components of the picture signal accentuated since the peaking coil presents a higher impedance to high frequencies than to low frequencies and that, as a result, the picture signal 70 supplied to the input circuit of the amplifier tube 75

42 includes substantially only the higher frequency components.

In a preferred embodiment, the plate 47 of the amplifier tube 42 is connected to the plate end of the plate resistor 34, this connection being 5 through a switch arm 58 and a switch contact point 59 in the circuit illustrated. It will be seen that the amplifier tubes 23 and 42 have a common output circuit whereby their outputs are added to give a signal which is the sum of the complete 10 picture signal supplied to the first channel 21 and the high frequency signal component supplied to the second channel 22.

By moving the variable tap 52 along the potentiometer 49, the gain of the amplifier tube 42 may 15 be varied whereby the amount of high frequency signal supplied to the common output circuits is varied to control the high frequency content of the picture signal supplied to the output tube 38.

The television receiver is provided with a suitable 20 separating circuit indicated at 61 which separates picture signals from synchronizing signals. The horizontal synchronizing signals and the vertical synchronizing signals are supplied from the circuit 61 to deflecting circuits 62 and 63, respectively. Deflecting coils 64 and 66 are supplied 25 with saw-tooth deflecting currents from the deflecting circuits 62 and 63, respectively, for scanning a fluorescent screen at the end of the cathode ray tube 41.

Other circuit connections than those described above may be employed. For example, the switch arm 58 may be moved to the dotted line position to make the contact with a switch contact point 67 30 whereby the plate 47 is connected to the junction point of the peaking coil 33 and the plate resistor 34. If the other switch 56 is left in the solid line position shown on the drawings, the high frequency components of the picture signal will be 35 accentuated more than when the amplifier is connected as first described. This is apparent from the fact that when the plate 47 is connected to the junction point of the peaking coil 33 and the plate resistor 34, the plate circuit of the amplifier tube 42 is almost purely inductive whereby the plate 40 impedance of the tube is much greater for high frequencies than for low frequencies. Consequently, the amplifier tube will amplify the higher 45 frequencies the greater amount.

Substantially the same results as those obtained 50 by the first described connection may be obtained by throwing switches 56 and 58 to the dotted line positions. The operation of the circuit connected in this way will be understood from the foregoing 55 description. All picture signal components are supplied to the two amplifier channels 21 and 22 without discrimination but the amplifier in the channel 22 amplifies the high frequency components more than the low frequency components, 60 whereby it accentuates the high frequency components in the resultant picture.

Referring to the amplifier circuit shown in Fig. 2, it differs from the circuit shown in Fig. 1 mainly in the manner in which the amplifier 65 channel 22 is designed for the purpose of accentuating the high frequency components of the picture signal. In the two figures, like parts are indicated by the same reference numerals. In the circuit shown in Fig. 2, the input circuit of the amplifier tube 42 in the channel 22 is coupled 70 to the output circuit of the amplifier 2 through a coupling condenser 71 having such small capacity that it presents a high impedance to the low frequency components of the picture signal. Therefore, more high frequency components than low 75

frequency components are supplied to the amplifier 42, whereby the output of the amplifier accentuates the high frequency content of the resultant picture signal.

- 5 It is preferred to accentuate the high frequency components still further by providing an inductance coil 12 adjacent to the control grid 44, this coil having the proper amount of inductance to make it resonate with the input capacity of the 10 amplifier tube 42 at the highest frequencies. This causes further accentuation of the high frequency components.

15 Various other designs may be employed for the purpose of accentuating the high frequency components of the picture signal in the amplifier channel 22. For example, in Fig. 3, where parts similar to those in Fig. 1 are indicated by like 20 reference numerals, the picture signal is supplied from the output circuit of the amplifier 2 to the input circuit of the amplifier 42 through a high-pass filter 13 consisting of a plurality of sections, each including a series condenser 14 and a shunt resistor 16.

25 Experience has indicated that it is desirable to advance the phase of the high frequency components of a picture signal with respect to the low frequency components. This can be accomplished by inserting a delay network 77 between the amplifier 2 and the amplifier 23 of the first channel 30 21 whereby all frequency components of a picture signal are delayed substantially the same amount. The high frequency components which appear in the output circuit of the amplifier 42 of the second channel 22 are not delayed and, 35 therefore, in effect are advanced in phase with respect to the signal supplied by the first amplifier channel. It will be apparent that when the outputs of the two amplifier channels are combined, the resultant signal includes high frequency components which have been advanced in phase with respect to the low frequency components.

40 It will be understood that the two amplifier tubes 23 and 42 in the two channels may be included in a single envelope, this being the pre-

ferred arrangement. In one amplifier embodying my invention, a 6F7 tube was employed, the triode part of this tube acting as the amplifier 23 and the pentode part acting as the other amplifier 42.

5 While I have illustrated and described only two amplifier channels connected in parallel for varying the frequency response curve of the complete amplifier, three or more such amplifier channels may be employed. For example, a third channel 10 may be designed to amplify the low frequency components of a picture signal more than the other components whereby both the high frequency response and the low frequency response of the television receiver may be adjusted for 15 the purposes described in my above-mentioned Patent No. 2,122,990.

20 It will be apparent from the foregoing description that various other modifications may be made in my invention without departing from the spirit and scope thereof, and I desire, therefore, that only such limitations shall be imposed thereon as shall be necessitated by the prior art and are set forth in the appended claim.

25 I claim as my invention:

In combination, an amplifier tube having a grid circuit and a plate circuit and adapted to amplify signals comprising components covering a wide frequency range, a plurality of amplifier channels each having an input circuit coupled to 30 said plate circuit, one of said amplifier channels including an amplifier tube having a plate circuit which includes a peaking coil and a plate resistor in series with said resistor located between said coil and the plate of said tube, the other of said 35 amplifier channels including an amplifier tube having a plate, and means for connecting said plate to the junction point of said coil and said resistor whereby the outputs of said amplifier channels add with the second amplifier channel 40 amplifying the high frequency components more than the lower frequency components.

WALDEMAR J. POCH.
